US00D843522S

(12) **United States Design Patent** (10) Patent No.: **US D843,522 S**
Miklvc et al. (45) Date of Patent: **** Mar. 19, 2019**

(54) **COVER FOR VIBRATING EXERCISE ROLLER**

(71) Applicant: **Hyper Ice, Inc.**, Irvine, CA (US)

(72) Inventors: **Jure Miklvc**, Kusterdingen (DE);
Silva Vitez, Kusterdingen (DE)

(73) Assignee: **Hyper Ice, Inc.**, Irvine, CA (US)

(**) Term: **15 Years**

(21) Appl. No.: **29/599,430**

(22) Filed: **Apr. 3, 2017**

(51) LOC (11) Cl. **21-02**

(52) U.S. Cl.

USPC **D21/692**

(57) **CLAIM**

The ornamental design for a “cover for vibrating exercise roller,” as shown and described.

DESCRIPTION

FIG. 1 is a front perspective view of the present design. FIG. 2 is a rear perspective view of the present design. FIG. 3 is a left side elevation view of the present design. FIG. 4 is a right side elevation view of the present design. FIG. 5 is a front elevation view of the present design. FIG. 6 is a rear elevation view of the present design. FIG. 7 is a top plan view of the present design. FIG. 8 is a bottom plan view of the present design. FIG. 9 is a front elevational cross-sectional view taken along the line 9-9 in FIG. 3; and, FIG. 10 is a side elevational cross-sectional view taken along the line 10-10 in FIG. 6.
